UNITED STATES PATENT OFFICE.

FRANZ CH. REINHARDT, OF PATERSON, NEW JERSEY.

BRAIDING-MACHINE.

SPECIFICATION forming part of Letters Patent No. 554,309, dated February 11, 1896.

Application filed November 13, 1895. Serial No. 568,810. (No model.)

To all whom it may concern:

Be it known that I, FRANZ CH. REINHARDT, a citizen of the United States, residing in Paterson, county of Passaic, and State of New Jersey, have invented certain new and useful Improvements in Braiding-Machines; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

The object of my present invention is to provide a braiding-machine with such means that the cheap common hairy fiber can be used as filler for the braids to be manufactured on said machine, and which braids, when finished, will be smooth, and the hairy portions of the filler will not penetrate its covering.

The invention consists in the combined guide and layer (or blade) and in the combination and arrangement of the various parts, substantially as will be hereinafter more fully described and finally embodied in the clauses of the claim.

Referring to the accompanying drawings, Figure 1 is a front elevation of a circular-braiding machine provided with my improvement, only those parts of the machine being shown which are necessary to fully illustrate the nature of my said invention. Fig. 2 is an enlarged detail view of the combined guide and layer; Fig. 3, a perspective view of the layer proper; Fig. 4, a detail top plan view of the guide proper.

In said drawings, *a* represents the circular frame of a braiding-machine, on which the spools and bobbins and their operating mechanism are arranged in the usual well-known manner. Traversing the circular frame and secured thereto by means of nuts and bolts *b*', or in any desired manner, is the bar or bridge *b*, to the center of which is secured the upwardly-extending stationary shaft or rod *c*. On the upper portion of said rod is arranged a tube *f*, having its top rounded off, as at *g*', and is secured to said rod by means of the set-screw *f*'. The upper portion of said tube forms a chamber for the reception of the block *g*, penetrated in its center by a

horizontally-arranged hole *g*' and provided with a vertical slot extending from the top of said block to the said hole *g*'. The block *g* is secured in the chamber of tube *f* by means of the set-screw *g*', which latter also serves to clamp the lower portion of the layer or blade *h* in the slot of block *g*.

The layer or blade *h* consists of a flat metal strip provided at about its center with a rectangular forwardly-projecting sleeve *h*', secured to said strip by solder or in any desired manner, or, if preferred, made integral with the same. The top portion *h* of said layer extends through a slot *i* of the horizontally-arranged arm *i*, adjustably secured to the lever *i*', which in turn is adjustably secured by means of nut and bolt *i* to a stud or pin *i* projecting downwardly from the bar *a*', which latter is a portion of the frame of the braiding-machine and does not need to be described in detail. The slot *i* must be of a size large enough to permit the passage of the finished braid through the same. On said bar *a*' is also arranged a bracket-frame *a* having the bearings for the rollers *m m*', between which the finished braid *B* passes, as in the usual well-known manner.

On the shaft *c* and below the tube *f* is secured by means of the set-screw *e* a sleeve *d*, having a horizontally-projecting plate *d*', provided with a series of openings *d* through which the hairy fibers *A A A* (used as fillers for the braids) are adapted to pass.

In operation, when the hairy fibers *A*, after passing through the guide-holes *d*, enter the square sleeve *h*', their hairy projections are laid flat on the fiber, and as soon as they leave the said sleeve they are, together with the top portion *h* of the blade *h*, covered up by the covering-threads *C*, and are thus prevented from penetrating the said covering. The braid is moved or slid upward on the said top portion *h* and leaves the latter as soon as it has passed through the slot *i*, when the covering-threads *C* on account of their elasticity will firmly bind on the fillers, as will be manifest.

From the foregoing it can be seen that the cheap hairy fiber can be used for the manufacture of smooth braids, and also that the number of fibers (as fillers) is immaterial. If more than three fibers are used, the layer *h* is removed and replaced by one having a sleeve

of a width equal to the combined diameters of the said fibers.

I do not intend to limit myself to the precise construction shown and described, as various alterations can be made without changing the scope of my invention; but

What I claim as new, and desire to secure by Letters Patent, is—

1. In a braiding-machine, the combination with the frame, of a vertically-arranged shaft on said frame, a plate projecting horizontally from said shaft and provided with a series of holes or openings, a tube adjustably secured to said shaft, and a rectangular sleeve carried by said tube, and removably secured thereto, all said parts adapted to operate substantially as and for the purposes described.

2. In a braiding-machine, the combination with the frame, of a vertically-arranged shaft on said frame, a guide-plate projecting horizontally from said shaft and adjustably secured thereto, a tube adjustably secured to said shaft and above said guide-plate, an upwardly-projecting blade supported by said tube, and a rectangular sleeve on said blade, all said parts adapted to operate substantially as and for the purposes described.

3. In a braiding-machine, the combination with the frame, of a vertically-arranged shaft on said frame, a guide-plate projecting horizontally from said shaft, a tube on said shaft, a block adjustably arranged in said tube, and

a rectangular sleeve supported by said block, all said parts adapted to operate substantially as and for the purposes described.

4. In a braiding-machine, the combination with the frame, of a vertically-arranged shaft on said frame, a guide-plate on said shaft, a tube on said shaft and above the guide-plate, a blade carried by said tube, a rectangular sleeve on said blade, and a slotted arm adjustably secured to the frame for the reception of the upper free end of said blade, all said parts adapted to operate substantially as and for the purposes described.

5. In a braiding-machine, the combination with the frame, of a vertically-arranged shaft on said frame, a guide-plate adjustably secured on said shaft, a tube on said shaft and above the guide-plate and having its upper end rounded off, a spring-block adjustably secured in said tube, a blade supported by said block, a rectangular sleeve on said blade and a slotted arm adjustably secured to the frame for the reception of the upper free end of the blade, all said parts adapted to operate, substantially as and for the purposes described.

In testimony that I claim the foregoing I have hereunto set my hand this 1st day of November, 1895.

FRANZ CH. REINHARDT.
